ROAD CONTRACTION JOINT

Robert R. Robertson, Chicago, Ill., assignor to The Translode Joint Company, Chicago Heights, Ill., a corporation of Illinois

Application August 19, 1937, Serial No. 159,830

10 Claims. (Cl. 94—18)

This invention relates to a road joint, and more particularly to a load transmission contraction joint adapted to be positioned to extend transversely across the roadway, and is made up of a plurality of reversed, staggered load transmission contraction units or spaced aligned units adapted to be staked in position upon the road sub-grade and having the upper ends connected, before the pouring of concrete, by means of a removable edging bar or by means of a cracking plate and cap, either of which is continuous across the roadway; said bar or cap being removable after the first pass of the screed or tamping machine to permit edging of the concrete road slabs and the formation of a top groove for the reception of a plastic filler such as asphalt or the like.

It is an object of this invention to provide a load transmission contraction joint consisting of a plurality of reversed, staggered load transmitting units, normally connected by means of a removable edging bar.

It is a further object of this invention to provide a contraction joint comprising spaced, aligned load transmission units connected by a cracking plate having a removable edging cap engaged thereon.

It is also an object of this invention to provide a contraction joint consisting of a plurality of spaced aligned contraction units which are connected by means of a cracking plate having an edging cap removably supported thereon before the pouring of concrete; said units and cracking plate adapted to be left embedded in the concrete, when the edging cap is removed to permit edging of the concrete slabs and the filling of the groove formed by the removal of said edging cap.

It is an important object of this invention to provide a road contraction joint adapted to extend transversely of a roadway and consisting of a plurality of load transmitting contraction units which in one form of the device may be spaced apart and reversed in staggered relation to one another, or which in another form may be spaced apart and aligned without being reversed; said units adapted to be held in position on the road sub-grade by means of stakes or the like. The contraction units are normally connected at their upper ends by means of either a removable edging bar or cap which is pulled out of the concrete after the first pass of the screed or tamper to permit edging of the road slabs and furthermore permit a plastic filling to

be deposited in the groove formed by the removal of the edging bar or cap.

Other and further objects of this invention will be apparent from the disclosures in the specification and the accompanying drawings.

The invention (in a preferred form) is illustrated in the drawings and hereinafter more fully described.

On the drawings:

Figure 1 is a fragmentary top plan view of a road contraction joint forming mechanism embodying the principles of this invention and showing the staggered arrangement of the contraction units with respect to the removable edging bar before the pouring of concrete to form the road slabs.

Figure 2 is an enlarged fragmentary isometric view of one of the contraction units associated with a fragmentary portion of the removable edging bar.

Figure 3 is an enlarged vertical transverse section taken on line III—III of Figure 1.

Figure 4 is a fragmentary top plan view of a modified form of road contraction joint forming mechanism in which the load transmission units are arranged in spaced, aligned relationship with respect to one another instead of being reversed or staggered as shown in Figure 1.

Figure 5 is an enlarged fragmentary side elevational view of the contraction joint forming mechanism shown in Figure 4 and illustrating the cracking plate for connecting the load transmission units with said cracking plate having an edging cap removably engaged thereon.

Figure 6 is an enlarged transverse detail section taken on line VI—VI of Figure 5.

Figure 7 is an enlarged fragmentary vertical detail section taken through the upper portion of the joint forming mechanism after the same has been embedded in concrete and after the space above the joint has been closed by a plastic filling.

Figure 8 illustrates a fragmentary top plan view of still another modified form of contraction joint forming mechanism wherein the load transmission units are reversed and staggered with respect to one another and are connected in their spaced relation by means of a cracking plate and a removable edging cap similar to the arrangement illustrated in Figure 5.

As shown on the drawings:

This invention relates to a transverse joint for roads and more particularly to a load transmission contraction joint forming mechanism adapted to be supported on the road sub-grade,

to extend across the roadway. The contraction joint forming mechanism consists of a plurality of alternately reversed and staggered load transmission contraction units which are temporarily connected before the pouring of the concrete, by a removable edging bar.

Each of the load transmission contraction units comprises a lower section and an upper section which slidably interfit with one another.

10 The lower section comprises an upright body plate 1, constructed of sheet metal, and having integrally formed on the lower edge thereof at substantially right angles, a base plate or foot 2 provided with an opening or aperture 3 for the reception of the lower tapered end of a stake 4. The base plate 2 has a portion thereof cut out and bent downwardly and rearwardly to lie in substantially the plane of the base plate 2 but projecting from the opposite side of the body plate 1 in the form of a brace plate 5 as clearly illustrated in Figure 2. Integrally formed at substantially right angles to the upper margin of the body plate 1, is a connecting plate or flange 6, the outer margin of which integrally connects up with a round, split anchoring sleeve or tube 7. Positioned parallel to the connecting plate or flange 6 and integral with the split anchoring sleeve 7 is a load transmitting plate 8 which is positioned to project across the plane 30 of the body plate 1 and through the vertical plane of the joint. As clearly illustrated in Figure 3 the load transmission plate 8 is wider than the connecting plate 6. As shown in Figure 3 the upper portion of the retaining stake 35 4 is provided with an arm or hook member 9 which is adapted to fit over the anchoring sleeve or tube 7 for holding the lower section of the load transmission unit staked in position upon the road sub-grade to hold the unit in position during the pouring of concrete, for the formation 40 of concrete road slabs on opposite sides of the contraction joint unit.

Interfitting with the lower section of the contraction joint unit, is an upper section comprising an upper body plate 10 having integrally formed at substantially right angles to the lower margin thereof, a connecting plate or flange 11 the bottom surface of which is in frictional engagement with the top surface of the load transmission plate 8 of the lower section of the joint unit. Integrally formed on the outer margin of the connecting plate 11, is a split anchoring sleeve or tube 12. Positioned parallel to the connecting plate 11 and integral with the split anchoring sleeve 12 is a load transmitting plate 13 which is also positioned to project across the plane of the body plate 10 and the lower body plate 1 into frictional sliding contact with the lower surface of the load transmitting plate 8 of the lower section of the joint unit. The two overlapping plates 8 and 13 separate the upper body plate 10 from the lower body plate 1 with the wide load transmitting plate of one section slidably fitting between the two plates of the other section.

65 The improved contraction joint units are arranged in reversed spaced staggered relation, as illustrated in Figure 1, across the roadway and are staked or otherwise integrally secured to the road sub-grade to hold the units in proper position.

The body plates 10 of the upper sections of the contraction joint units are connected one to another by means of a removable edging bar 14. Rigidly secured in staggered relation on opposite

75 sides of the edging bar 14 are a plurality of metal

strips 18, the intermediate portions of which are deflected to provide sockets 15 adapted to seat over the upper ends of the tops of the body plates 10 of the contraction joint units. If desired, the upper side portions of each top body plate 10 may be bevelled at 16 to facilitate engagement of the edging bar socket on said body plate. Struck inwardly from the socket portion 15 of each strip 18 is a spring retaining lip or tongue 17 adapted to spring into tight frictional engagement with the top body plate 10, as clearly illustrated in Figure 3, to hold the removable edging bar supported in position for connecting the staggered contraction joint units.

With the contraction joint units arranged in 15 reversed staggered relation across the roadway and secured in position by means of the stakes 4 or the like and with the edging bar 14 removably engaged on the upper ends of the upper body plates 10, concrete is poured on opposite sides 20 of the joint forming mechanism to form road slabs. The concrete which forms the road slabs, embeds the transverse portions of the road joint units and the load transmission or anchoring sleeves 7 and 12 forming a part thereof, so that 25 the upper and lower sections of each unit are, anchored in the road slabs on opposite sides of the joint forming mechanisms. After the completion of the pouring of the concrete and after the first pass of the screed or tamper for levelling 30 the top surface of the concrete, the edging bar 14 is lifted off of the upper end of the top body plates 10 and is removed from the concrete leaving a transverse groove across the roadway. By the use of proper edging tools the upper edges of 35 the concrete slabs, formed on opposite sides of the joint forming mechanisms, are properly edged and the groove is then filled with a plastic filler such as asphalt or the like.

The improved road contraction joint forming 40 mechanisms of this invention afford an arrangement whereby the amount of sheet metal required for the forming of the joint is materially reduced in view of the fact that the staggered units are comparatively short and are spaced 45 apart thereby requiring less material than in the case of a contraction joint which is continuous across the roadway. The edging bar 14, which is removably engaged on the upper ends of the contraction joint units, may be repeatedly reused thereby affording an additional saving.

After a contraction joint mechanism has been supported on a road sub-grade transversely of the roadway and is embedded between concrete, the edging bar 14 is removed after which the edges 55 of the concrete slabs are rounded or finished off and the groove left by the removal of the edging bar is then filled with a plastic material to seal the top of the joint. The construction affords an arrangement whereby the concrete slabs on opposite sides of the joint are connected one with the other at spaced intervals by the contraction joint units, the sections forming the same being anchored in the adjacent road slabs. This arrangement permits loads which are applied to a road slab on one side of the joint to be transmitted through the joint unit to the road slab on the opposite side of the joint. With the contraction of the road slabs, the interfitting portions of the upper and lower sections of each of 60 the joint units move outwardly with respect to one another to widen the middle portion of the joint with the separation of the road slabs.

Figures 4 to 7 inclusive illustrate a modified form of road contraction joint which consists of 70

a plurality of spaced and aligned load transmission contraction units, which as clearly illustrated in Figure 4 are supported on a road sub-grade transversely of the road with all of the units facing the same direction and disposed in a straight row in spaced parallel relation with respect to one another.

The group of load transmission contraction units are of substantially the same construction 10 as the units illustrated in Figures 1 to 3 inclusive.

In the modified form of the joint forming mechanism illustrated in Figures 4 to 7 inclusive, each of the load transmission units is constructed identically to the units illustrated in Figure 3, 15 and like parts are, therefore, indicated by corresponding reference numerals. The contraction units in the modified form of the construction are also retained in position by means of stakes 4.

The body plates 10 of the upper sections of the 20 contraction joint units are connected one to another by means of a cracking plate 19 constructed of metal, fiber or other suitable material. The cracking plate 19 has struck from the upper marginal portion thereof, a plurality of spaced hangers or hooks 20 all of which project from one side 25 of the cracking plate 19 and are engaged over the upper marginal edges of the body plates 10 of the top sections of the contraction joint units. The hook members 20 are so formed that the 30 cracking plate 19 is securely held in position connecting the aligned contraction joint units. In case it is desired to rigidly connect the cracking plate 19 with the body plates 10 of the spaced units, said cracking plate 19 may be spot-welded 35 to the plates 10 or otherwise rigidly fastened thereto.

For the purpose of permitting proper edging of the upper corners of the concrete road slabs between which the joint forming mechanism is 40 embedded, a U-cross sectioned or inverted channel edging cap 21 is removably engaged over the upper edges of the cracking plate 19 and the body plates 10 of the separate units.

With the contraction joint units arranged in 45 aligned relationship across the roadway and secured in position by means of stakes 4 or the like, and with the cracking plate 19 connecting the units and supporting the removable edging cap 21 in place as illustrated in Figure 6, concrete 50 is poured on opposite sides of the joint forming mechanisms to form the road slabs 22 and 23 (Figure 7). The concrete which forms the road slabs, embeds the transverse portions of the road joint units so that the upper sections of the units 55 are anchored in the road slab 22, while the lower sections of the units are anchored in the road slab 23. After the completion of the pouring of the concrete and after the first pass of the screed or tamper for levelling the top surface of the concrete, the edging cap 21 is lifted off of the upper 60 edge of the cracking plate 19 to leave a top groove in the concrete permitting proper edging of the upper corners of the road slabs. After the edging of the slabs, the top groove of the joint is 65 filled with a plastic filler such as asphalt or the like to form a top filler or seal 24 to embed the upper margins of the body plates 10 and the cracking plate 19.

Figure 8 of the drawings illustrates another 70 modified form of contraction joint forming mechanism wherein the load transmission joint units are arranged in spaced reversed staggered relation, similar to the arrangement illustrated in Figure 1, and are connected by means of a cracking 75 plate 19 and a removable edging cap 21. The

edging cap 21 is removable after the pouring of concrete to form a top groove for the reception of a filler of plastic material for sealing the top of the joint.

It will of course be understood that various 5 details of construction may be varied through a wide range without departing from the principles of this invention, and it is, therefore, not the purpose to limit the patent granted hereon otherwise than necessitated by the scope of the ap- 10 pended claims.

I claim as my invention:

1. A contraction joint forming mechanism comprising a plurality of reversed, staggered load transmission units, each comprising slidably interfitting sections, means for securing the units in position during the pouring of concrete, a continuous edging bar, socket members on the edging bar for engagement with the upper ends of the load transmission units, and latching means 15 forming a part of the socket members and frictionally engaging the upper portions of the load transmission units for supporting the edging bar in position until after the pouring of concrete 20 to form road slabs on opposite sides of the joint 25 forming mechanism.

2. A load transmitting device for forming a contraction joint between concrete road slabs, said device comprising a plurality of reversed, staggered load transmission units, each embedded 30 in the concrete road slabs at opposite sides of the joint, and each of said units comprising reversed interfitting sections each formed with plate members disposed transversely of the joint with the plate members positioned in slidable overlapping 35 engagement with one another, a continuous edging bar, socket members secured on opposite sides thereof for removable engagement over the upper ends of said load transmission units, and resilient means struck from the socket members and having 40 resilient engagement with the upper portions of said units for releasably holding the edging bar in position and connecting the load transmission units one with the other.

3. A load transmission contraction joint forming mechanism for embedding between adjacent concrete road slabs, said joint forming mechanism comprising a plurality of separated load transmitting units, each constructed of a top section and a bottom section adjustably interfitting 45 one another, each of said sections comprising a straight plate, an angled plate and a split sleeve integrally connecting said plates with the straight plate of one section projecting between the straight plate and the angle plate of the other section, a base plate integrally formed on each of 50 said lower sections for positioning beneath one of the road slabs, and means struck from the base plate and projecting beneath the opposite road slab.

4. A load transmission contraction joint forming mechanism for embedding between adjacent concrete road slabs and comprising a plurality of separated load transmitting devices, each of said devices constructed of interfitting adjustable sections, each section consisting of a straight plate, an angled plate and a split sleeve integrally connecting said plates, one section of each of said devices having a base plate formed thereon and 55 projecting beneath one of the road slabs, and a member struck from the base plate and projecting across the joint beneath the opposite road slab.

5. A load transmission contraction joint forming mechanism for embedding between and sepa- 75

- rating concrete road slabs, said mechanism comprising a plurality of load transmitting units, with each unit comprising an upper section and a lower section slidably interfitting therewith, an apertured base plate integrally formed on the lower section and projecting beneath one of the road slabs, and a member struck from the base plate and directed across the joint beneath the opposite road slab.
10. In a concrete construction, a load transmitting joint forming mechanism embedded between adjacent concrete road slabs, said mechanism comprising a plurality of separated load transmitting units each consisting of reversed slidably interfitting upper and lower sections, each section including a pair of plates integrally connected by a bight portion, with a plate of one section slidably projecting between and in frictional contact with both of the plates of the other section, and base members formed on each of said lower sections with one of said base members projecting beneath one of said road slabs and the other base member projecting across the joint beneath the adjacent road slab.
15. 7. A contraction joint forming mechanism including in combination a plurality of spaced load transmission contraction units and means for connecting the same in spaced relation to one another, said means comprising a continuous bar member, sockets formed on the sides thereof, and resilient latching means forming part of the sockets for releasable engagement with the contraction units.
20. 8. A road joint former comprising a plurality of load transmission units aligned in spaced, staggered relation with respect to one another, and means for connecting said units, said means comprising a continuous bar, socket members alternately formed on opposite sides thereof for engagement with the load transmission units, and resilient means struck inwardly from said sockets for frictional engagement with the load transmission units to hold said edging bar detachably engaged in position.
25. 9. A joint forming mechanism including in combination a plurality of load transmission units arranged in spaced, parallel relation with respect to one another, a cracking plate connecting said units, means struck from said cracking plate for supporting the cracking plate on said units, and an edging means supported on the cracking plate to enclose said means and also connecting said units.
30. 10. A road joint forming mechanism comprising a plurality of load transmission units, means for supporting the units in spaced, parallel relation on a road sub-grade, a cracking plate connecting all of said units, hook members on said cracking plate and engaging the units to support the cracking plate in position, and an edging cap removably engaged over the upper margin of the cracking plate to enclose said hook members and also connecting said units with one another.

ROBERT R. ROBERTSON.
